(57) **CLAIM**

The ornamental design for a lotion dispenser, as shown and described.

DESCRIPTION

FIG. 1 is a top perspective view of a lotion dispenser, showing the lotion dispenser incorporated into a cap disposed on a lotion bottle both of which are indicated in broken lines and do not form part of the design;

FIG. 2 is a top perspective view thereof showing the lotion dispenser incorporated into a cap which is indicated in broken lines and does not form part of the design;

FIG. 3 is a top plan view thereof;

FIG. 4 is a left side view thereof;

FIG. 5 is a front view thereof;

FIG. 6 is a right side view thereof;

FIG. 7 is a bottom plan view thereof;

FIG. 8 is a top perspective view of a second embodiment of the lotion dispenser, showing the lotion dispenser incorporated into a cap disposed on a lotion bottle, both of which are indicated in broken lines and do not form part of the design;

FIG. 9 is a top perspective view thereof showing the lotion dispenser incorporated into a cap, which is indicated in broken lines and does not form part of the design;

FIG. 10 is a top plan view thereof;

FIG. 11 is a left side view thereof;

FIG. 12 is a front view thereof;

FIG. 13 is a right side view thereof;

FIG. 14 is a bottom plan view thereof;

FIG. 15 is a top perspective view of the embodiment of FIG. 1 shown in a different environment; showing the lotion dispenser incorporated into a cap disposed on a lotion bottle both of which are indicated in broken lines and do not form part of the design;

FIG. 16 is a top perspective view thereof showing the lotion dispenser incorporated into a cap which is indicated in broken lines and does not form part of the design;

FIG. 17 is a top plan view thereof;

FIG. 18 is a left side view thereof;

FIG. 19 is a front view thereof;

FIG. 20 is a right side view thereof; and,

FIG. 21 is a bottom plan view thereof.

The broken line showing of a cap and bottle is for illustrative purposes only and forms no part of the claimed design.
